Charles W. Hall,

BY

Geo. P. Kimmel. ATTORNEY.

UNITED STATES PATENT OFFICE.

CHARLES W. HALL, OF VALPARAISO, INDIANA.

COMBINED CONTAINER AND SUPPORT.

Application filed August 2, 1926. Serial No. 126,626.

This invention relates to a combined container and support designed primarily for the reception of candies, handkerchiefs, gloves or other articles of merchandise for which the container is capable of storing, and has for its object to provide, in a manner as hereinafter set forth, a novel original, ornamental, distinctive, attractive, strong, durable, portable and efficient combined container and support for storing and displaying articles of merchandise or for any other purposes for which it is found applicable.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a side elevation of a combined container and support in accordance with this invention.

Figure 2 is a top plan view thereof.

Figure 3 is a front elevation.

Figure 4 is a section on line 4—4 Figure 1.

A combined container and support, in accordance with this invention, in appearance is a miniature simulation of an aeroplane and with the container forming what may be termed the wings of the plane and the support set up as a simulation of the fuselage of the aeroplane provided with a landing carriage.

Referring to the drawings in detail the support which is referred to by the reference character 1 consists of a flat bar of substantial length standing on one of its lengthwise edges and formed with an upstanding tail piece 2 provided at its top edge with an ornament 3.

At the point of joinder of the tail piece with the remaining part of the support a cushioning element 4 is secured to the bottom edge thereof. The support intermediate its ends is formed with a cut-out portion 5 which forms a socket for the reception of the retainer which is referred to generally by the reference character 6. The forward terminal portion of the bar 1 is tapered to provide a nose 7. Secured to and projecting from

the forward end edge of the support 1, is a revoluble member 8 which is in the form of a duplex propeller blade. The member 8 is mounted upon a pivot 9 and the latter is headed for retaining the member 8 thereon. Between the head of the pivot 9 and the member 8 a washer 10 is positioned.

Secured to the bottom edge of the support 1, at a point between its vertical median and its forward end is a carriage formed of a bracket 11 provided with a pair of oppositely extending trunnions 12, upon which wheels 13 are revolvably mounted. Retaining devices 14 engage in the trunnions 12 for the purpose of maintaining the wheels 13 thereon. The support 1, at each side of the forward terminal thereof, is provided with a series of ornamentalations as indicated at 15.

The container as shown comprises an open top body portion 16 having a closure 17 hinged thereto as at 18. As shown the container 6 is of rectangular contour, but it is to be understood that it can be of any suitable design. The front wall of the container 6 is ornamented on its outer face and at each side of the support 1 as indicated at 18 and the top of the hinged closure 17 is ornamented as at 19. The container 6 is of materially greater length than the width of the support 1 and the lower face of the bottom 20 of the container is formed with a transversely extending groove 21 which receives the bottom wall of the socket 5, see Figure 4 whereby the container 6 is connected to the body portion 1 or rather to the support 1.

The support is of rectangular cross section, of materially greater width than its thickness and of materially greater length than its width. The carriage is of a length materially greater than the thickness of the support, is disposed forwardly of the vertical median of the latter, and is secured centrally of its top to the bottom edge of the support.

The providing of the support with the rollers 13 permit of the same being shifted from any point desired, and owing to the manner in which the container 6 is connected to the support 1, the container can be readily removed therefrom when occasion requires. Any suitable article of merchandise, for which the container is applicable, can be stored therein. When displaying the contents of the container, the closure 17 is swung open. If desired the container can be pro-

vided with any suitable means for latching the closure in closing position. The support is overbalanced rearwardly.

It is thought the many advantages of a combined container and support therefor, in accordance with this invention can be readily understood, and although the preferred embodiment of the invention is as illustrated and described, yet it is to be understood that changes in the details of construction can be had which will fall within the scope of the invention as claimed.

What I claim is:

1. A container support comprising a flat bar disposed on its lower longitudinal edge and formed with a cut-out portion opening at the upper longitudinal edge of the bar and providing a socket forming means for receiving and securing a container to the bar, and a supporting carriage of the wheeled type having its top edge, intermediate its ends, secured against said lower longitudinal edge directly below the base of said socket forming means, the wheels of said carriage disposed laterally with respect to each side face of the bar.
2. A container support comprising a flat bar disposed on its lower longitudinal edge and formed with a cut-out portion opening at the upper longitudinal edge of the bar and providing a socket forming means for receiving and securing a container to the bar, and a supporting carriage of the wheeled type having its top edge, intermediate its ends, secured against said lower longitudinal edge directly below the base of said socket forming means, the wheels of said carriage disposed laterally with respect to each side face of the bar, the base of said socket forming means being positioned in close proximity to said lower longitudinal edge.
3. A container support comprising a flat bar disposed on its lower longitudinal edge and formed between its transverse median and forward end with a cut-out portion opening at the upper longitudinal edge of the bar and providing a socket forming means for receiving and securing a container to the bar, and a supporting carriage of the wheeled type having its top edge, intermediate its ends, secured against said lower longitudinal edge directly below the base of said socket forming means, the wheels of said carriage disposed laterally with respect to each side face of the bar, and a cushioning element secured to and depending from said lower longitudinal edge at a point in proximity to the rear termini of the latter.
4. A container support comprising a flat bar disposed on its lower longitudinal edge and formed between its transverse median and forward end with a cut-out portion opening at the upper longitudinal edge of the bar and providing a socket forming means for receiving and securing a container to the bar, and a supporting carriage of the wheeled type having its top edge, intermediate its ends, secured against said lower longitudinal edge directly below the base of said socket forming means, the wheels of said carriage disposed laterally with respect to each side face of the bar, and a cushioning element secured to and depending from said lower longitudinal edge at a point between the transverse median of said bar and the rear termini of the latter and of less height than the height of the carriage.
5. A mobile container support comprising a flat bar of substantial length disposed on its lower longitudinal edge and formed between its transverse median and forward end with a rectangular cut-out portion opening at the upper longitudinal edge of the bar and providing a socket forming means for receiving and securing a container to the bar transversely of the latter, and a wheeled carriage disposed transversely with respect to the bar and having its top edge, intermediate its ends, secured against said lower longitudinal edge directly below and centrally with respect to the base of said socket forming means, the wheels of said carriage disposed laterally with respect to the side faces of the bar.
6. A mobile container support comprising a flat bar of substantial length disposed on its lower longitudinal edge and formed between its transverse median and forward end with a rectangular cut-out portion opening at the upper longitudinal edge of the bar and providing a socket forming means for receiving and securing a container to the bar transversely of the latter, and a wheeled carriage disposed transversely with respect to the bar and having its top edge, intermediate its ends, secured against said lower longitudinal edge directly below and centrally with respect to the base of said socket forming means, the wheels of said carriage disposed laterally with respect to the side faces of the bar, and a cushioning element secured to and depending from said lower longitudinal edge of the bar at a point in proximity to the rear termini of the latter.

In testimony whereof, I affix my signature hereto.

CHARLES W. HALL
